UNITED STATES PATENT OFFICE.

EMERY M. HAMILTON, OF NEW YORK, N. Y., ASSIGNOR, BY MESNE ASSIGNMENTS, TO THE NORTH AMERICAN MACHINE COMPANY, OF WEST VIRGINIA.

TYPE-WRITING MACHINE.

SPECIFICATION forming part of Letters Patent No. 444,491, dated January 13, 1891.

Application filed February 26, 1890. Serial No. 341,688. (No model.)

To all whom it may concern:

Be it known that I, EMERY M. HAMILTON, of the city, county, and State of New York, a citizen of the United States, have invented 5 certain new and useful Improvements in Type-Writing Machines, of which the following is a full, clear, and exact description, reference being had to the accompanying drawings, forming part of this specification.

10 My invention relates generally to that class of type-writing machines in which the type are carried by vibratory type-bars and are adapted to print at a common printing-point, and in which the paper-carriage is moved 15 over the face of the type at the printing-point with a step-by-step movement; and my invention relates more particularly to certain improvements upon the type-writing machine invented by me for which Letters Patent No. 20 357,670 were granted February 15, 1887.

My invention consists in the devices and their combinations hereinafter set forth, and more at length recited in the claims.

Figure 1 is a plan of a type-writing machine containing my invention. Fig. 2 is a vertical central section of the same. Fig. 3 is a view in detail, partly in section, of parts of the machine to which my present improvements particularly relate. Fig. 4 is an obverse plan of my improved type-bar supporting disk or annulus, and Fig. 5 is a reverse plan of the same. Fig. 6 is a perspective view of the C-spring, hereinafter described.

In the drawings, the type-bars are illustrated at *a* arranged radially in a circular series, with their outer ends pivoted to a corresponding series of rocking arms *b*, which arms have formed on them, respectively, segmental pinions *b'*, journaled in the disk or annulus *C*, the said bars being fulcrumed intermediate their ends on an annular rib *c* on said disk *C*. The said bars *a* pass through vertical slots *c'* *c''*, formed, respectively, in upwardly-projecting annular flanges *c'* and *c''* on the upper or obverse face of the disk *C*, and have play therein over and upon their fulcrums and between said fulcrums and a corresponding annular rib *d*, which depends from an annulus *D*, that is supported on the

rim or upper edge of the flange *c'* of disk *C*. 50 The rocking of the arms *b* acts to vibrate the bars *a* on their fulcrums and to slide them thereon back and forth endwise, so as to carry the printing-type to and from the common printing-point of the type-bar series. 55 The said rocking motion is given to said arms *b* by means of levers *b'*, on which are formed toothed segments *b''*, which mesh, respectively, with the pinions *b'* on the arms. The levers *b'* are actuated by means of key-levers *b''*, provided with keys *b'''*, and the rods *b''* intermediate the levers *b'* and *b''*. By depressing a key *b'''* its lever *b'* operates to throw a rod *b''* upward, and said rod impinging upon a lever *b''* vibrates said lever upward, and thereby 65 communicates the described movement to the type-bar. This is clearly illustrated in Fig. 2. Upon the release of the key *b'''* a spring *C'* operates to retract the lever *b'* and bring it downward to its original position. 70

D' is the base-plate of the machine, which supports a disk or plate *D''*, which in turn supports the disk or annulus *C*, as hereinafter set forth. The key-levers *b''* may be fulcrumed, as shown at *b''*, Fig. 2, on the base *D'*, 75 and may play between the said base and the disk or plate *D''*, the rods *b''* preferably having bearings in said base and plate, as shown.

D'' is a post set perpendicularly in the base at the center of the type-bar series or system. 80 Upon this post a sleeve *D'* is adapted to have play longitudinally, and said sleeve is provided with the annular flange *d'*, as shown. The inner ends *b''* of the levers *b'* of the series thereof engage the flange *d'*, whereby 85 the upward vibration of the outer ends of said levers *b'* operates to depress the sleeve *D'* on said post *D''*.

D'' is what is generally known as the "universal lever" of the machine, by means of 90 which the desired movement of the paper-carriage is attained. Said lever *D''* is fulcrumed at *d''*, and one arm *d''* thereof extends to and engages the sleeve *D'*, while its other arm *d''* extends to and engages the lever *e*, which lever *e* serves to engage and disengage the dog *e'* to and from rack *e''* on the paper-carriage *E*. When the sleeve *D'* is depressed by the end *b''*

of one of the levers b^2 in the act of printing by a corresponding type-bar a of the series, the lever D^5 is thereby vibrated, so that its arm d^5 operates to swing the lever e , so as to shift 5 the dog e' from one tooth to another of the rack e^2 , thereby effecting the feed or movement of the paper-carriage. The carriage traverses the ways e^3 and carries the usual cylindrical platen e^4 and its pressure-roller e^5 . 10 My present invention relates primarily to the disk C and the combination therewith of the described type-bars a and their actuating-levers b^2 .

In the patent hereinbefore referred to— 15 namely, No. 357,670—the levers h , which correspond to the levers b , are shown and described as fulcrumed upon an upwardly-projecting flange on an annulus which is separate from the disk on which the type-bars are 20 fulcrumed, and which is independently seated on the disk or plate B' , corresponding to the plate D^2 , while the rocking arms and their segmental pinions are journaled in another and separate annulus, which is supported 25 above the plate B' , and upon which annulus the type-bar disk is mounted; but the objection to and disadvantages of such an arrangement of the said parts are obvious. In the first place the multiplicity of separate 30 devices makes the machine expensive and complicated in construction. Furthermore, it being necessary that the several annular disks on which, respectively, the rocking-arm pinions are journaled, the type-bars and levers are fulcrumed, should be arranged and 35 adjusted concentrically with great exactitude in the machine, in order that the said movable parts shall have the proper and accurate motions in the operation of the machine.

The assembling of the several disks and the parts mounted thereon is an exceedingly difficult and laborious work, necessitating mechanical skill of a high order. 40

The object of my present invention is to so 45 simplify the structure of the machine that its parts may be readily and quickly assembled with the required accuracy. To this end the disk C , upon the upper side of which the type-bars a are fulcrumed and have play, as 50 described, is provided with the depending annular flange c^5 on its under side, the said flange being furnished with the edge or projections c^6 , preferably inwardly turned, while the inner ends b^8 of the levers b^2 are formed 55 with the hook ends b^9 preferably upwardly and outwardly turned, and thus adapted to engage said edge c^6 of the flange c^5 , as shown in Figs. 2 and 3. It is also preferable that the flange c^5 should be of such a depth as to adapt 60 it to serve as a support or standard for the disk C on the plate D^2 by the rim of said flange resting upon said plate, as shown, in which case the flange c^5 will have the vertical slots c^7 from its lower edge inwardly, and the projections c^6 will be formed on the flange at the 65 bottom of each slot. The rim of the disk C is desirably provided with radial slots c^8 , in

which the pinions b' of the rocking arms b may be journaled, and in which the said arms and segments b^3 may have play, as shown. 70 It will be found advantageous to cast or form the disk C with its annular rib c and slotted annular flanges c^3 c^4 on its obverse face, the radial slots c^8 at its rim, and the depending slotted annular supporting-flange c^5 having 75 the projections c^6 on its reverse face integral in one piece. By means of this described disk C it is evident that the said annular rib and flanges may be initially constituted in an exact concentric arrangement relatively 80 to each other, and that the type-bars and their rocking arms and the levers b^2 may be readily and accurately assembled on the disk, which, with these said parts mounted upon it, is then ready to be seated upon the plate 85 D^2 in the machine. In seating the disk C on the plate D^2 an aperture c^9 , central in the disk, may fit upon and be fixed to the post D^3 , while the edge of the flange c^5 rests upon the face of said plate D^2 . 90

A further feature of my present invention consists in the combination, with the described levers b^2 and their supporting-disk, of the **C**-spring C' . One extremity of this **C**-spring engages the upper edge of a lever b^2 , 95 which may be effected by bifurcating the said spring end, as at c^{10} , so that the lever edge is embraced by the bifurcation and yet the movement of the spring end over the lever edge when the spring is flexed and again relaxed 100 is permitted. The other end of the **C**-spring engages the under side of the disk C , which may be effected by a hook c^{11} on the said end of the spring adapted to catch against the bottom of a radial rim-slot c^8 in the disk, as 105 shown. The disk is preferably annularly recessed at c^{12} on its under face, as shown, to permit the play of the **C**-springs when they are flexed. The advantages of these **C**-springs in connection with the described disk 110 C in the rapid, accurate, and economical assembling of the various parts are apparent.

What I claim as my invention, and desire to secure by Letters Patent, is—

1. In a type-writing machine, the combination, with the levers b^2 intermediate the key-levers and type-bars and provided, respectively, at their inner ends with hooks b^9 , of a disk C , upon which the type-bars are supported and fulcrumed, having on its under face a depending annular flange c^5 , provided with the edge or projections c^6 , whereby said levers are fulcrumed on said disk, substantially as and for the purpose set forth. 115

2. In a type-writing machine, the combination, with the levers b^2 intermediate the key-levers and type-bars and provided, respectively, at their inner ends with hooks b^9 , of a disk C , having on its under face a depending annular flange c^5 , adapted in depth to serve 120 as a support or standard for said disk and having the vertical slots c^7 and the projections c^6 at the bottom of said slots, respectively, whereby said levers are fulcrumed on said 125

disk-flange and have play in said vertical slots, substantially as and for the purpose set forth.

3. In a type-writing machine, the combination, with the type-bars *a* and the levers *b*², provided on their inner ends, respectively, with upwardly and outwardly turned hooks *b*⁹, of the disk *C*, having on its obverse face the annular rib *c*, on which the type-bars are fulcrumed and have play and on its reverse face the depending annular flange *c*⁵, provided with the inwardly-turned edge or projections *c*⁶, on which said levers are fulcrumed at their said hooked inner ends, substantially as and for the purpose set forth.

4. In a type-writing machine, the combination, with the type-bars *a* and their rocking arms *b* and pinions *b*', and the levers *b*², having toothed segments *b*³ on their outer ends and provided at their inner ends with the hooks *b*⁹, of the disk *C*, on the obverse face of which the type-bars are fulcrumed and have play, provided at its rim with the radial slots *c*⁸, in which said rocking-arm pinions are journaled, and on its reverse face with the annular depending flange *c*⁵, having the edge or projections *c*⁶, on which said levers are fulcrumed at their said hooked inner ends, substantially as and for the purpose set forth.

5. In a type-writing machine, the combination, with the type-bars *a* and the levers *b*², provided at their inner ends with hooks *b*⁹, of the disk *C*, having on its obverse face the annular type-bar fulcrum-rib *c* and the upwardly-projected vertically-slotted annular flanges *c*³ and *c*⁴, in which the type-bars have play on their said fulcrum-rib, and having on its reverse face the depending annular flange *c*⁵, provided with the edge or projections *c*⁶, on which said levers are fulcrumed by their said hooked inner ends, substantially as and for the purpose set forth.

6. In a type-writing machine of the class described, the single-lever system supporting

disk *C*, having on its obverse face the upwardly-projecting vertically-slotted flanges *c*³ and *c*⁴, together with the annular rib *c* intermediate said flanges, on its obverse face the depending annular flange *c*⁵, adapted to serve as a support or standard for said disk and provided with the vertical slot *c*⁷ and the edge or projections *c*⁶ at the bottom of said slots, and on its rim the radial slots *c*⁸, said disk, with its flanges and projections and slotted, as described, being formed integral in one piece, substantially as and for the purpose set forth.

7. In a type-writing machine, the combination, with the levers *b*², provided at their inner ends with the hooks *b*⁹, and the disk *C*, provided on its lower face with the depending annular flange *c*⁵, having edge or projections *c*⁶, on which said levers are fulcrumed by their said hooked inner ends, of the **C**-springs *C*', having respectively the bifurcated ends *c*¹⁰ engaging the said levers and their other ends seated on or against said disk, substantially as and for the purpose set forth.

8. In a type-writing machine, the combination, with the levers *b*², provided at their inner ends with the hooks *b*⁹, and the disk *C*, provided on its lower face with the depending annular flange *c*⁵, having the edge or projections *c*⁶, on which said levers are fulcrumed by their said hooked inner ends, and provided on said lower face with the annular recess *c*¹² beyond said depending flange, of the **C**-springs *C*', having respectively the bifurcated ends *c*¹⁰ engaging said levers and their other ends seated on or against said disk and playing when flexed by the movement of said levers in said annular recess in said disk, substantially as and for the purpose set forth.

EMERY M. HAMILTON.
